US00D361980S

United States Patent [19]

Chen

[11] Patent Number: Des. 361,980

[45] Date of Patent: ** Sep. 5, 1995

[54] BATTERY SEAT

[76] Inventor: **Han-Liang Chen**, 1Fl., No. 6-2, Lane 78, Sungchiang Rd., Taipei, Taiwan

[**] Term: **14 Years**

[21] Appl. No.: **32,507**

[22] Filed: **Dec. 20, 1994**

[52] U.S. Cl. **D13/119**

[58] Field of Search **D13/119; 429/96, 98, 429/99, 100; 439/500, 698**

[57] CLAIM

The ornamental design for a battery seat, as shown.

DESCRIPTION

FIG. 1 is a front-left-top perspective view of a battery seat, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a cross-sectional view taken along line 8—8 of FIG. 1; and,

FIG. 9 is a cross-sectional view taken along line 9—9 of FIG. 1.

FIG. 1

FIG. 5

FIG. 6

FIG. 2

FIG. 4

FIG. 7

FIG. 3

FIG. 8

FIG. 9
